PORABLE SURGICAL COLLECTION UNIT

Edmond O. Pratt, Los Angeles, Calif.

Application November 15, 1955, Serial No. 38,902

Term of patent 14 years

(Cl. D83—1)

The figure is a perspective view of the portable surgical collection unit as seen from one side and end thereof, the other side and end of which corresponds thereto, showing my new design.

I claim:

The ornamental design for a portable surgical collection unit, substantially as shown.
